Claims priority, application Denmark Aug. 4, 1960
2 Claims. (Cl. 20—53)

This invention relates to a window construction preferably for use in buildings, which may be subjected to very much sunshine and the object of the invention is to provide means by which it is possible to cut-off an essential part of the heat radiation from the sunshine and to reestablish the transparency of the window.

It is a further object of the invention to provide such a window with means by which a material capable of reflecting an essential part of the heat radiation may easily be placed in the space between two plates of transparent material forming the window and also to provide means for displacing said material from said space.

Further objects will appear from the following description.

In a window construction consisting of at least two plates of transparent material placed parallel to one another and forming a narrow space, the edges of the plates being surrounded by an airtight frame closing said space, the fundamental features of the invention consist in the provision of a chamber along one horizontal side of the frame, said chamber containing an easy-running granulate, the window construction being further provided with means for transferring the granulate from the chamber to the space and vice versa.

The invention will be best understood with reference to the accompanying drawing, which shows a cut-out part of a window construction in accordance with the invention.

The drawing shows a part of a window suspended in a fixed wallframe 1 and comprising a windowframe 2 enclosing two closely spaced panes 3 and 4, a pair of grooves 5 and 6 being provided on the inside of the major part of the frame for receiving the edges of the panes 3 and 4 while a rib 7 is provided between these grooves to provide the predetermined spacing of the panes 3 and 4. The window also comprises an extra pane 8 positioned in the frame 2 by means of a groove 9 formed between the frame 2 itself and a last 10, the groove 9 receiving the edge of the pane 8.

On the frame 2 is a pivot fitting 11 receiving a pivot pin 12 carried by a tapsocket 13 which in turn is secured to the fixed wallframe 1. Only one of these pivoting arrangements is shown in the drawing but a corresponding arrangement is of course provided on the opposite side of the frames 1 and 2.

The upper edges of the glass panes 3 and 4 extend upwardly into a chamber 14 in the upper part of the frame 2. Between the glass pane 3 and the frame 2 is clamped a flap 15 the free portion of which overhangs the upper edges of the panes 3 and 4, and along the free edge of this flap 15 a rod 16 is attached in order to increase the weight of the flap 15.

The outer edge of the flap 15 or the rod 16 is connected by means of a cord 17 with the free end of an arm 18 the other end of which is fixed to a pivoting rod 19 extending through a packing 20 to the outside of the frame 2, where it is connected to an arm 21 the free end of which is pivotally connected with a rod 22 terminating at its lower end in a handle 23.

The chamber 14 contains a granulate or the like such as small glass beads 24 and when the rod 22 is pulled the pivoted rod 19 is turned to move the arm 18 upwardly whereupon the flap 15 is lifted and the glass beads slide

2

downwardly into the space between the two glass panes 3 and 4.

The chamber 14 is closed at the top by a resilient wall 25 fastened to the inside of the chamber by means of flanges 26 and 27. The resilient wall serves the purpose of equalization of varying pressures arising as a result of temperature variations in the air contained in the space between the glass panes 3 and 4 and in the chamber itself, and to allow such equalization the frame 2 has a hole 28 connecting the space above the resilient wall 25 with the outside air. This insures that no air can enter the space comprising the chamber and the space between the glass panes 3 and 4, and thus by initially drying the air in this space any formation of condensed moisture is obviated. Means for absorbing moisture may also be placed in the chamber.

When the glass beads fill up the space between the glass panes 3 and 4 the window will have the appearance of frosted glass such as sandblasted glass and although this somewhat reduces the passage of visible light this loss of light is not of any significance and generally an advantage in the case of direct radiation from the sun. The window provides a diffused light and at the same time reduces substantially the passage of heatrays.

When it is desired again to render the window clear, it is turned about the pins 12, whereby the flap 15 will be carried to hang downward and thus allow the glass beads to slide into the chamber 14.

When the window is then turned back to its closed position the flap 15 due to the action of the weight of the rod 16 will fall back against the top-edges of the glasspanes 3 and 4, and will thus prevent the glass beads from flowing back into the space between the glasspanes until the flap 15 is lifted again by pulling on the rod 22.

The use of glass beads has proved to be extremely advantageous particularly because the use of uncoloured glass beads prevents any colouring of the light passing through the window. Nevertheless it is obvious that coloured glass beads or other granulates which are generally sufficiently finely divided may be used in order to reduce or colour the light if required. One of the advantages in using a granulate is that this has no tendency to adhere to the glass panes and thus when the window has been turned to remove the granulate from the space between the glass panes 3 and 4 a completely clear and transparent window results.

Alternatively the removal of the granulate from the space between the glass panes 3 and 4 may be conveniently achieved as by a pumping device which conveys the material to the chamber 14, for example, through a duct in the frame 2.

What I claim is:

1. In a window construction comprising at least two plates of transparent material placed generally parallel to one another and defining a space therebetween, an airtight window frame disposed around said plates and pivotally mounted in a wall frame for movement into different vertical positions, a chamber extending along one horizontal side of said frame, an easy running granulate in said chamber in sufficient quantity for filling said space between said plates and passage means permitting the transfer of said granulate from said chamber to said space and from said space to said chamber, said passage means comprising a longitudinal slot defined in said frame and extending substantially the full length of said horizontal side and including means for opening and closing said passage means.
2. In a window construction comprising at least two plates of transparent material placed generally parallel to one another and defining a space therebetween, an airtight window frame disposed around said plates and piv-

70

totally mounted in a wall frame for movement into different vertical positions, a chamber extending along one horizontal side of said frame, an easy running granulate in said chamber in sufficient quantity for filling said space between said plates, passage means comprising a longitudinal slot defined in said frame and extending substantially the full length of said horizontal side, and means

including a horizontally disposed flap for opening and closing said passage means.
